SHEET AND SIGNATURE HANDLING
MECHANISMJoseph E. Meyer, Westerly, R. I., assignor to C. B.
Cottrell & Sons Company, Westerly, R. I., a
corporation of Delaware

Application August 5, 1942, Serial No. 453,614

9 Claims. (Cl. 164—84.5)

In sheet and signature handling mechanisms of the type in which successive sheets are partially severed from a web traveling at a certain speed, the tabs which connect the sheets to the web have been broken by the pull exerted on the sheets by the grippers or impaling pins carried by the cylinders which rotate at a higher surface speed than the speed of the traveling web.

It has been found that it is not desirable to depend upon the pull of the sheet grippers or impaling pins for breaking the tabs because where the grippers are used a too harsh cam would be required for operating the grippers and where impaling pins are used the pins would tear away from the partially connected sheets rather than to separate the sheets from the web.

The object of my invention is to provide means independent of the sheet grippers, impaling pins or other sheet engaging devices, for wholly separating the partially separated sheets and thus relieve the sheet engaging devices from the strain of breaking the tabs which connect the sheets with the web.

The tab breaking means comprises a yielding member carried by one of the cylinders in position to press the leading end of the partly severed sheet against the surface of the other cylinder with sufficient pressure to break the tabs between the sheet and its web as the sheet grippers or impaling pins engaging the leading end of the sheet.

A practical embodiment of my invention is represented in the accompanying drawings, in which

Fig. 1 represents a detail vertical section of a sheet and signature handling mechanism, the tab breaker being shown about to contact the leading end of the partly severed sheet;

Fig. 2 represents a similar view showing the positions of the parts as the tab breaker has separated the sheet from the web and the grippers have grasped the leading end of the sheet;

Fig. 3 represents a similar view showing the parts in the positions, they assume after the tab breaker has moved away from the sheet and the sheet has been forwarded a slight distance by the grippers;

Figs. 4, 5 and 6 represent views similar to Figs. 3, 4 and 5 respectively illustrating impaling pins as the sheet engaging devices rather than the grippers;

Fig. 7 represents a detail plan view of the web on an enlarged scale, showing the tabs which connect a partially severed sheet to the web;

Fig. 8 represents a horizontal detail section of the tab breaker; and

Fig. 9 represents a vertical section taken in the plane of the line 9—9 of Fig. 8.

The upper and lower pairs of feed rolls 11, 11 and 12, 12 feed the web 13 at a predetermined speed. The pair of coacting cutters 14, 14 are located between the upper and lower pairs of feed rolls, one of which cutters is provided with the usual knives 15, 15 provided with notches (not shown) along their cutting edges for partially severing the successive sheets 16 from the web, leaving tabs 17 connecting the successive sheets to the web. A pair of guides 18, 18 serve to direct the web 13 through the upper and lower pairs of feed rolls and the intermediate pair of rotary cutters. The pair of sheet carrying cylinders 19, 19^a which may be either delivery, collecting, transfer or folding cylinders are shown as the cylinder 19^a being provided with grippers 20 in Figs. 1, 2 and 3 and the corresponding cylinders 19^b as provided with impaling pins 21 in Figs. 4, 5 and 6. These rotary sheet carrying cylinders 19, 19^a or 19, 19^b are driven at a predetermined higher speed than the speed of the web 13.

A tab breaker 22 extends along the periphery of the cylinder 19 into position to coact with the periphery of the other cylinder 19^a or 19^b adjacent its sheet engaging device, which tab breaker is pressed outwardly by springs 23 into position to press the leading end of the partly severed sheet 16 against the peripheral surface of the coacting cylinder 19^a or 19^b. The continued rotation of these two cylinders 19, 19^a or 19, 19^b will cause the tab breaker to separate the sheet 16 from its web 13 by breaking the tabs 17 and thus causing the sheet to immediately take the surface speed of the said cylinders.

At the same time the grippers 20 or impaling pins 21, as the case may be, will engage the leading end of the sheet and convey the sheet around its cylinder 19^a or 19^b.

This tab breaker 22 is provided with notches 24 for accommodating the grippers 20 or impaling pins 21. This yielding tab breaker 22 is herein shown as slidably mounted in a holder 25, the springs 23 being located in sockets 26 in said holder. Pins 27 are employed for limiting the outward movement of the tab breaker 22.

It will be seen from the above description that the tab breaking strain is entirely eliminated from the sheet grippers or impaling pins by the introduction of the separate tab breaker 22. It will also be understood that the tab breaker 22 is particularly well adapted for machines handling products of different sizes where the acceleration of the sheet carrying cylinders becomes

so excessive as to make it impractical to employ grippers to break the tabs because of the harshness of the gripper cams required for operating such grippers. This tab breaker also makes it possible to operate the cut-off mechanism at much higher speeds than would ordinarily be possible.

It is evident that various changes may be resorted to in the construction, form and arrangement of the several parts without departing from the spirit and scope of my invention, and hence I do not intend to be limited to the particular embodiment herein shown and described, but what I claim is:

1. In a sheet and signature handling machine, means engaging a web traveling at a certain speed for partially severing successive sheets from the web, a pair of cylinders rotating at a higher surface speed than the web, means on one cylinder arranged to press the leading end of a partially separated sheet against the other cylinder to wholly separate the sheet from the web, and means on the said other cylinder for engaging the sheet as it is wholly separated from the web.

2. In a sheet and signature handling machine, means engaging a web traveling at a certain speed for partially severing successive sheets from the web, a pair of cylinders rotating at a higher surface speed than the web, yielding means on one cylinder arranged to press the leading end of a partially separated sheet against the other cylinder to wholly separate the sheet from the web, and means on the said other cylinder for engaging the sheet as it is wholly separated from the web.

3. In a sheet and signature handling machine, means engaging a web traveling at a certain speed for partially severing successive sheets from the web, a pair of cylinders rotating at a higher surface speed than the web, means on one cylinder arranged to press the leading end of a partially separated sheet against the other cylinder to wholly separate the sheet from the web, and grippers on the said other cylinder for engaging the sheet as it is wholly separated from the web.

4. In a sheet and signature handling machine, means engaging a web traveling at a certain speed for partially severing successive sheets from the web, a pair of cylinders rotating at a higher surface speed than the web, yielding means on one cylinder arranged to press the leading end of a partially separated sheet against the other cylinder to wholly separate the sheet from the web, and grippers on the said other cylinder for engaging the sheet as it is wholly separated from the web.

5. In a sheet and signature handling machine, means engaging a web traveling at a certain

speed for partially severing successive sheets from the web, a pair of cylinders rotating at a higher surface speed than the web, means on one cylinder arranged to press the leading end of a partially separated sheet against the other cylinder to wholly separate the sheet from the web, and impaling pins on said other cylinder for engaging the sheet as it is wholly separated from the web.

6. In a sheet and signature handling machine, means engaging a web traveling at a certain speed for partially severing successive sheets from the web, a pair of cylinders rotating at a higher surface speed than the web, yielding means on one cylinder arranged to press the leading end of a partially separated sheet against the other cylinder to wholly separate the sheet from the web, and impaling pins on said other cylinder for engaging the sheet as it is wholly separated from the web.

7. In a sheet and signature handling machine, a pair of coacting rotary cutters for partially severing successive sheets from a web traveling at a certain speed, a pair of cylinders rotating at a higher surface speed than the web, a spring seated tab breaker on one cylinder arranged to press the leading end of a partially separated sheet against the peripheral surface of the other cylinder to wholly separate the sheet by breaking the tabs connecting the sheet with the web, and sheet engaging devices on said other cylinder for engaging the sheet as it is wholly separated from the web.

8. In a sheet and signature handling machine, a pair of coacting rotary cutters for partially severing successive sheets from a web traveling at a certain speed, a pair of cylinders rotating at a higher surface speed than the web, a spring seated tab breaker on one cylinder arranged to press the leading end of a partially separated sheet against the peripheral surface of the other cylinder to wholly separate the sheet by breaking the tabs connecting the sheet with the web, and grippers on said other cylinder for engaging the sheet as it is wholly separated from the web.

9. In a sheet and signature handling machine, a pair of coacting rotary cutters for partially severing successive sheets from a web traveling at a certain speed, a pair of cylinders rotating at a higher surface speed than the web, a spring seated tab breaker on one cylinder arranged to press the leading end of a partially separated sheet against the peripheral surface of the other cylinder to wholly separate the sheet by breaking the tabs connecting the sheet with the web, and impaling pins on said other cylinder for engaging the sheet as it is wholly separated from the web.

JOSEPH E. MEYER.
